ATTORNEY

UNITED STATES PATENT OFFICE

EMMA V. HUSSON, OF BROOKLYN, NEW YORK

SILENCER MOUTHPIECE FOR TELEPHONE TRANSMITTERS

Application filed April 11, 1932. Serial No. 604,515.

This invention relates to new and useful improvements in a silencer mouthpiece for telephone transmitters.

The invention has for an object the construction of an article of the class mentioned which is characterized by a tubular member closed at the front end and adapted for attachment at the rear on a telephone transmitter, and a mouthpiece rotative on the front of the tubular member and having apertures adapted to align with similar apertures on the front of the tubular member and to be moved to a position in which the apertures are out of alignment.

As a further object it is proposed to provide means for limiting turning of the mouthpiece to one or the other of the positions mentioned.

Furthermore, as another object, it is proposed to arrange a flange upon the periphery of the tubular member and a second flange on the mouthpiece rotatively secured to the first flange by reason of the edges of the latter being turned over the edges of the adjacent flange.

Furthermore, the invention proposes the provision of means whereby the mouthpiece automatically assumes a position in which the apertures are out of line or a position in which the apertures are in alignment or a condition wherein the mouthpiece maintains either position when placed in it.

Furthermore, the invention proposes the construction of a device of the class described which is of simple durable construction, dependable in use and efficient in operation, and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a transverse longitudinal sectional view of a device constructed according to this invention.

Fig. 2 is an elevational view looking in the direction of the line 2—2 of Fig. 1.

Fig. 3 is an elevational view looking in the direction of the line 3—3 of Fig. 1.

Fig. 4 is a view similar to Fig. 1 but illustrating a modified construction. 55

The silencer mouthpiece, according to this invention, comprises a tubular member 10 closed at the front end 11 and adapted for attachment at the rear upon a telephone transmitter. To facilitate the attachment at the rear the tubular member is formed with threads 12 adapted to engage corresponding threads on the telephone transmitter. A mouthpiece 13 is rotative on the front of the tubular member 10 and has a plurality of apertures 14 adapted to align with similar apertures 15 in the front end 11 of the tubular member or to assume a position in which the apertures are out of line. In Fig. 2 the apertures are shown in aligned arrangement. In Fig. 3 they are shown out of line. 65

The rotative mounting of the mouthpiece 13 is accomplished by a flange 16 projecting from the mouthpiece and in intimate contact with a flange 17 projecting from the tubular member. The edge 18 of the flange 17 is turned over the edge of the flange 16. A means is provided for limiting rotation 70 of the mouthpiece to a position in which the apertures 14, 15 are in alignment or in which they are out of alignment. This means comprises a pin 19 projecting from the flange 16 and passing through a slot 20 80 formed in the flange 17. 85

A means is also provided for urging the mouthpiece 13 into a position in which the apertures 14, 15 are aligned and adjustable to urge the mouthpiece into a position in 90 which they are out of alignment and further adjustable to hold the mouthpiece in either position. This means comprises a resilient member 21 attached upon the head of the pin 19 and adapted to engage any one of a plurality of eye members 22, 23 and 24 projecting from the flange 17. When the resilient member 21 is connected with the eye member 22 the mouthpiece 13 will be urged in one direction and when connected with 100

the eye member 23 it will be urged in the other direction. When the resilient member 21 is connected with the eye member 24 the mouthpiece 12 will maintain either position 5 in which it is placed. The free end of the resilient member 21 is formed in the shape of a hook adapted to engage the eye member.

In Fig. 4, a variation of the invention has been disclosed in which the flange 17 is 10 shown with its outer end 18' spun around the edge of the flange 16'. Furthermore, the flange 16' is secured to and projects a small distance in from the edge of a tubular neck portion 25 connected with the rear of 15 the mouthpiece 13. This tubular portion 25 engages within a recess 26 at the root of the flange 17. In other respects this form of the invention is identical to the form previously disclosed.

20 In operation, a person may adjust or hold the mouthpiece 13 so that the openings 14, 15 are in alignment and then conversation may be held through the transmitter. Should the speaker desire to talk with others 25 near the transmitter but also desire to prevent the transmission of the conversation over the transmitter, he may adjust, turn or allow the mouthpiece to assume a position in which the apertures 14, 15 are out of 30 alignment.

While I have shown and described the preferred embodiment of my invention, it is to be understood that I do not limit myself to the precise construction herein disclosed 35 and the right is reserved to all changes and modifications coming within the scope of the invention as defined in the appended claims.

Having thus described my invention, what I claim as new, and desire to secure by 40 United States Letters Patent is:—

1. A silencer mouthpiece for telephone transmitters, comprising a tubular member closed at the front end and adapted for attachment at the rear on a telephone transmitter, a mouthpiece rotative on the front of 45 said tubular member and having apertures adapted to align with or be out of alignment with similar apertures on the front end of said tubular member, and means for urging said mouthpiece into one of said rotative positions and adjustable for urging the mouthpiece into the other of said rotative positions and further adjustable to hold the mouthpiece in either of said positions.

50 55 2. A silencer mouthpiece for telephone transmitters, comprising a tubular member closed at the front end and adapted for attachment at the rear on a telephone transmitter, a mouthpiece rotative on the front 60 of said tubular member and having apertures adapted to align with or be out of alignment with similar apertures on the front end of said tubular member, and means for urging said mouthpiece into one of said 65 rotative positions and adjustable for urging

the mouthpiece into the other of said rotative positions and further adjustable to hold the mouthpiece in either of said positions, comprising a pin fixed in the mouthpiece, eye elements fixed upon the tubular member 70 on each side of the pin, another eye element radially relative to the pin and the tubular member, and resilient means engageable between the pin and any of the eye elements.

In testimony whereof I have affixed my 75 signature.

EMMA V. HUSSON.
